UNITED STATES PATENT OFFICE.

ISAAC A. BAUM, OF CHICAGO, ILLINOIS.

METAL FRAME FOR DOORS.

Application filed March 6, 1928. Serial No. 259,432.

My invention relates to means for framing wall openings and particularly to a frame composed entirely of metal and adapted to be installed with a minimum of labor.

5 A fundamental idea is to provide a one piece structure comprising a jamb, a stop, suitable molding and plaster terminals, the parts being formed from a sheet of metal without difficult bends. Combined with the 10 described structure are means for positioning the frame relative to a wall, together with means adapted to co-operate with a wall anchor for securing the frame against movement away from the face of the wall.

15 The invention will be more readily understood by referring to the accompanying drawing, in which—

Fig. 1 is a transverse sectional view through a frame and wall arranged in accordance with my invention, and

20 Fig. 2 is a sectional view on the line 2—2 of Fig. 1.

In the drawings I have illustrated a section through one element only of the frame, it being understood that both vertical and horizontal members are similarly formed. The frame itself comprises a sheet of metal bent to provide the flat jamb 10 having a door stop 11 formed outwardly from the metal 25 of the jamb. At the two edges of the jamb, the metal is bent backwardly and thence outwardly to provide the jog 12, thence backwardly in any approved manner to provide a decorative trim. The sheet is then rebent to 30 provide the break 13, and the margin, either in the form shown at 14 in the upper side of the view, or at 15 in the lower side of the view, is bent to provide a plaster terminal. The surface 16 acts as a plaster ground, the 35 plaster being indicated at 17.

As a means for positioning the frame element relative to tile, indicated at 18, I provide the channel member preferably composed of two parts, the flat part 19 abutting 40 and being welded to the inside face of the jamb, while the flange 20 projects rearwardly and is adapted to lie alongside of the tile. At the inner end of the flat portion 19, the metal is rebent as at 21 and projected into 45 the space within the hollow stop, the arrangement being such that a continuous dove-tail slot is provided in the space within the stop. An anchor 22 having a T shaped head 23 is

imbedded in the mortar between adjacent tiles with its head in the position shown in the 55 drawings. This serves to securely hold the frame relative to movement in any direction. The anchor together with the flanges 20 insure a rigid connection of the frame to the wall under blows imparted to the stop by a 60 door, while the anchor securely holds the frame against movement away from the edge of the wall.

The construction is capable of considerable modifications and I do not wish to be limited 65 except as indicated in the appended claims.

I claim:

1. In metal trim for wall openings, the combination of a sheet of metal bent to provide a jamb, molding and plaster terminal, 70 a channel secured to the inner face of the jamb with its flanges projecting inwardly to provide positioning means for tile and means integral with said channel and cooperating with said jamb to provide a dovetail slot 75 adapted to receive a wall anchor.

2. In combination, a sheet of metal bent to provide a jamb, a molding and a stop, an angular metal piece secured to the inner face 80 of the jamb, a flange of said piece acting as means for positioning the metal parts relative to a wall, a portion of said metal piece being rebent to enter the space within said stop and to assist in forming a dovetail groove for the reception of an end of a wall 85 anchor.

3. In combination, a sheet of metal bent to provide a door frame having a jamb and a hollow stop, an angular metal piece secured to the inner face of the jamb, a flange of said 90 piece acting as means for positioning the metal parts relative to a wall, a portion of said metal piece being rebent to enter the space within said stop and to assist in forming a dovetail groove for the reception of an 95 end of a wall anchor.

4. In combination, a sheet of metal bent to provide an integral door frame having a jamb, a molding terminating in a plaster terminal and a hollow door stop on the outer 100 face of the jamb, a channel formed in two pieces, each piece having a flat part secured to said jamb and a rearwardly projecting flange adapted to position the frame relative to a wall, the margins of said pieces opposite 105 to the flange margins being rebent, and pro-

jected into the space within said stop, together providing an undercut groove adapted to receive the end of a wall anchor.

5. A metal frame for doors, comprising in combination, a sheet of metal bent to provide a jamb and a hollow stop, and an angular member welded to the inside face of the jamb and having flanges projecting rear-

wardly to lie along side of a masonry wall for holding the frame member against lateral movement, and members projecting from said angular member into said hollow stop to form an under-cut groove for an anchor.

In testimony whereof I have affixed my signature.

ISAAC A. BAUM.
